UNITED STATES PATENT OFFICE

2,474,302

GLASSWARE-FORMING APPARATUS

Edward Danner, Newark, Ohio

Application December 6, 1943, Serial No. 512,996

9 Claims. (Cl. 49—171)

1

The present invention relates to the manufacture of glassware and particularly to the manufacture of glass tubing. By the present invention it is possible to produce glass tubing having a wall thickness greater than tubing produced on the presently known commercial machines. It is also possible to produce a higher quality glass tubing at greater drawing speeds and with lower production costs.

The present invention is applicable to drawing apparatus of the stationary type such as is disclosed in my copending application Serial No. 380,179, filed February 24, 1941, now United States Patent No. 2,390,925. It is also applicable to the well-known Danner machine which embodies an inclined rotatable mandrel as illustrated in my Patent No. 1,219,709. In either type of apparatus the use of the present invention effects a substantial improvement in the quality of the resulting product and results in the other advantages mentioned above.

While certain features of the apparatus disclosed herein are also shown in the above-mentioned copending application, the novel features of the present invention will be readily apparent from the detailed description set forth hereinafter.

In the accompanying drawings I have shown a preferred embodiment and certain modifications of my invention. It will be understood, however, that my invention may be otherwise embodied or practiced without departing from the spirit and scope thereof.

In the drawings,

Figure 1 is a vertical sectional view through the forehearth of a glass-melting tank, showing my invention incorporated therein, with parts in elevation;

Figure 2 is an enlarged section on the same plane as Figure 1 showing more particularly a forming chamber having forming means therein suspended below the forehearth;

Figure 2a is a perspective view of a detail;

Figure 3 is a horizontal section taken along the plane of line III—III of Figure 2;

Figure 4 is a vertical section through a modified type of tube-forming means adapted to be suspended in a forming chamber such as that shown in Figure 2;

Figure 5 is a vertical section through a modified form of apparatus including a mandrel journaled for rotation on an axis inclined to the vertical; and

Figure 5a is a partial section showing a portion of Figure 5 to enlarged scale.

Referring in detail to the drawings and, if for the present, to Figures 1 and 2, my invention is there illustrated as applied to a glass-melting tank 10 of conventional construction, having a forehearth 11 projecting therefrom and carried

thereby. The glass-melting tank 10 is connected to the forehearth 11 through an outlet 12 controlled by a vertically movable gate 13. The forehearth has a bottom discharge port 14. A distributor 15 in the form of a cylinder of refractory material is placed over the port 14. The distributor is supported on wedge blocks 16 slidably disposed in ports 17 extending radially through the side walls of the forehearth. The wedge blocks are held in position by plugs 18 fitting into the ports 17. Tangential burner ports 19 are formed in the side walls of the forehearth and a cover 20 is disposed on top thereof. A manifold 21 extends around the upper edge of the forehearth for supplying fuel to burners firing into the ports 19. The manifold is secured to brackets 22 mounted on the forehearth. The details of construction thus far described are also disclosed in my copending application above referred to.

A forming chamber 23 suspended below the forehearth is adapted to receive a stream of molten glass descending therefrom through the port 14 at a rate depending on the vertical adjustment of the mandrel 57 and the viscosity of the molten glass. The construction of the forming chamber 23 is generally similar to that disclosed in the aforementioned copending application and also in my copending application, Serial No. 423,255, filed December 17, 1941, now Patent No. 2,462,805 for Glassware-forming apparatus. The chamber 23 comprises a cylindrical, refractory-lined, open-bottomed shell suspended on hanger bars 24 projecting downwardly from the forehearth. The lining of the chamber is laid up within the top and bottom plates 23a and 23b and a sheathing 23c. An annular manifold 25 below the chamber has burners 26 adapted to fire upwardly and around the interior of the chamber to control the viscosity of the glass descending therethrough. The manifold is carried on brackets 27. A frusto-conical flame deflector 28 is carried on rods 29 upstanding from a Y-shaft arm 30. The arm 30 is carried on a rack bar 31 slidable vertically in a tube 32. A pinion 33 journaled in a housing 34 projecting laterally of the tube 32 meshes with the rack bar whereby on rotation of the pinion by means of a crank 35, the deflector 28 may be adjusted vertically.

As clearly shown in the drawings, the upper end of the chamber 23 is spaced below the bottom of the forehearth 11. To control the draft upwardly through the chamber, I provide a damper 36 in the form of a refractory-lined ring surrounding the reduced upper end of the chamber. The ring is vertically adjustable, being carried on brackets 37 one of which is mounted on a vertical shaft 38, the other being mounted on nuts threaded on screws 39 projecting upwardly from the shoulder near the upper end of the chamber. The shaft 38 has a threaded portion

cooperating with a hub 40 on the outside of the chamber. A hand wheel 41 on the lower end of the shaft 38 permits the latter to be turned. A chain and sprocket drive 42 connects the shaft 38 with the nuts on the screws 39 whereby the rotation of the shaft moves the damper 36 vertically.

A readily replaceable refractory disc 43 having a central hole therethrough in which a metal bushing 44 is positioned is provided beneath the port 14. A gasket 45 is disposed between the disc and the bottom of the forehearth. The disc is supported on tapered screws 46 threaded in lugs 47 secured to the bottom of the forehearth. As shown in Figure 3, the disc 43 is embraced by metal straps 48 connected by bolts 49. The straps are set into a circumferential groove in the disc. Sleeves 50 on the bolts 49 are engaged by the tapered ends of the screws 46. The disc 43 may thus be forced into firm engagement with the bottom of the forehearth.

A blow pipe 51 extends downwardly through a hole in the forehearth cover 20, the distributor 15, the port 14 in the bottom of the forehearth and the bushing 44 in the disc 43. A protective sheathing 51a of refractory material surrounds that portion of the pipe 51 above the forming chamber 23. The pipe is connected to a suitable source of air under pressure. A bar 52 is provided at one end with means for clamping the pipe 51. The other end of the bar is threaded to receive a hand wheel 52a having a threaded bore, disposed in a bearing 52b carried on one of the brackets 22. By turning the wheel 52a the pipe 51 may be adjusted horizontally in respect of the openings in the bottom and top of the forehearth. A ring 53 is secured on the pipe 51 at a level somewhat below the top of the chamber 23. A refractory sleeve 54 surrounding the pipe rests on the ring 53. A bushing 55 surrounds the pipe 51 near its lower end and is supported on a split ring 56, the two halves of which fit into a circumferential groove in the pipe. The bushing 55 is raised when the halves of the ring 56 are set in place. The latter are securely held in position when the bushing is lowered to the illustrated position.

A refractory mandrel 57 having a ring 58 at the lower end thereof surrounds the greater portion of the pipe 51 within the chamber 23. Spacer and supporting blocks 59 like that shown in detail in Figure 2a are spaced circumferentially of the bushing 55 and serve to support the ring 58 and mandrel 57 thereon. It will be observed that the blocks 59 are tapered at the top adjacent their inner faces and at the bottom adjacent their outer faces. This facilitates the flow of an annular stream of glass downwardly between the ring 58 and the bushing 55 and aids the reunion of the portions of the stream separated by the blocks. Spacer blocks 60, which are like blocks 59 in construction, are disposed between the sleeve 54 and the tube 57.

Spaced ribs 61 are welded to the pipe 51 near the lower end thereof and are also welded to a nut 62 which is threaded on the end of the screw 64. The screw and nut hold in position the cup shaped member 65 which is positioned at the bottom end of the tube 51. This cup shaped member has an integral bottom plate having air holes 63 thereon to permit air to pass from the lower end of the blow pipe. The upper end of the sleeve 65 engages the lower end of the bushing 55. Radial pins 66 are threaded into or otherwise secured to the member 65. The pins 66

support a plurality of nesting, spaced, coaxial cylinders or shells 67 which constitute means for shaping the glass stream descending through and around the mandrel 57 into a continuous cylinder of the desired size. Such means is claimed broadly in my copending application, Serial No. 380,179.

The glass stream descending from the forehearth is restricted by the bushing 44 and the disc 43 but after passing therethrough flows downwardly in layer form along the outside of the mandrel 57 as well as on the inside thereof. The layer of glass flowing downwardly along the outside of the mandrel has one surface only in contact with the mandrel. This is likewise true of the inner layer of glass. During this flow of the glass it is tempered, with the result that a better product is obtained. At the lower end of the mandrel the glass strikes the shells 67 which serve to spread or enlarge the stream, which is already in the form of a hollow cylinder, and shape it. The glass flows between and around the shells and the separate streams unite at the lower ends of the shells, i. e. at the ware-forming plane, to form a single wall tube. A continuous length of tube may thus be drawn downwardly from the glass flowing over the shells 67. After the tube has traveled a sufficient distance from the forming chamber, it cools and becomes rigid enough to be handled by any convenient receiving and conveying means. Various sizes of tube, of course, may be drawn, depending primarily on the speed of draw and also on the viscosity of the glass and the rate at which the tube cools after leaving the forming chamber. The shells 67, as stated, are particularly advantageous in forming tubes of larger diameter and of greater wall thickness but they serve also to permit drawing smaller sizes of tubes at a rate greater than that obtainable with tube-forming apparatus previously known.

Figure 4 illustrates a modification of a portion of the structure shown in Figure 2. In Figure 4, the blow pipe 51 is provided with a bushing 55' carried on a split ring 56 in the same manner as the bushing 55. A mandrel 57' rests on the bushing 55' and is provided at its upper end with a spacer disc 67'. With this construction, it will be evident that glass flowing downwardly from the forehearth will flow around the exterior only of the mandrel 57' and will pass downwardly therealong in layer form with one surface only in contact with the mandrel.

A cup shaped closure member 63' is secured to the pipe 51 in the same manner as the cup shaped member 65 and supports the shells 67 by means of the pins 66 as already explained. This closure member 63' has openings 63a therein to permit air to pass from the lower end of the blow pipe.

Figures 5 and 5a show the application of glass-forming means, including a plurality of nesting, coaxial shells, to a mandrel mounted for rotation on an axis inclined to the vertical, in the manner shown in my Patent No. 1,219,709. As shown in the drawings, a blow pipe 70 is journaled in a suitable bearing 71 for rotation about an inclined axis and extends below a glass delivery channel 72 and in alignment with the outlet 73. The pipe is provided with a beveled gear 70' whereby it may be driven by any convenient mechanism and with a swivel joint 74 connected to a suitable source of air under pressure. A refractory tube 75 is disposed coaxially on the pipe 70 adjacent the lower end thereof and serves as a mandrel to shape into roughly tubular form a stream of glass

descending through the outlet 73. The lower end of the tube 75 rests on a collar 16 secured to the end of the pipe 10, the lower end of the tube being of frusto-conical shape. A spacer collar 17 is disposed on the pipe adjacent the upper end of the tube 75 and serves to centralize the tube with respect to the pipe. An internally threaded bushing 18 is secured inside the lower end of the pipe 10. A plug 19 is fitted into the bushing. Pins 20 extending radially from the plug support a plurality of nesting, coaxial shells 21 and 21' disposed coaxially with the pipe 10 and tube 75, the outer shell extending vertically above the remaining shells in order to provide for the maintenance and proper distribution of glass on the tops of the shells. The plug 19 has a hole 22 extending longitudinally therethrough.

The shells 21 serve to shape the glass descending along the tube or mandrel 75 into a cylinder from which a continuous length of tubing may be drawn. By the use of these shells it is possible to draw tubing having a thicker wall than has been possible heretofore with the known tube-drawing machines. It is also possible to draw tubing either with a thick or a thin wall at speeds considerably in excess of those which have been possible heretofore. The spaced coaxial shells provide for distribution and feeding of large quantities of glass over a relatively wide area at the ware-forming plane at the bottom ends of the shells. Appreciably more glass can be accumulated at the ware-forming plane by using a multiple shell type shaping element than is possible where the regular type of mandrel, such as is shown in my prior Patent No. 1,219,709, is used. Where the shells are used on the lower end of the regular type of mandrel, greater flexibility in regard to rate of production, size and wall thickness is obtainable.

It will be apparent from the foregoing description and explanation that the invention provides glass-forming means of novel construction adapted to receive a downflowing stream of glass and convert it into a continuous length of tube. The glass-forming means disclosed herein have advantages over such means as have been known heretofore in respect to simplicity of construction and convenience of operation.

Although I have illustrated by a preferred embodiment with certain modifications, it will be recognized that changes in the construction or arrangement of parts illustrated may be made without departing from the scope of the appended claims.

I claim:

1. In glass-forming apparatus, a blow-pipe extending through means for delivering a downwardly flowing stream of molten glass, a member fitting over the lower end of the pipe and supported thereon, pins extending radially from said member, and a plurality of spaced coaxial shells mounted on said pins coaxially of said pipe adapted to receive glass flowing downwardly around said pipe.

2. Apparatus as defined by claim 1 characterized by a nut having ribs extending transversely across the pipe adjacent its lower end, and means securing said member to said nut.

3. In glass-forming apparatus, a blow-pipe extending through means for delivering a downwardly flowing stream of molten glass, a refrac-

tory tube surrounding the lower portion of the pipe and spaced therefrom, means carried on the pipe for supporting the tube at its lower end, means carried on the pipe for spacing the upper end of the tube therefrom, and a plurality of nested, coaxial shells mounted on the lower end of the pipe adapted to receive glass flowing downwardly on the exterior of said tube.

4. Apparatus as defined by claim 3, characterized by said spacing and supporting means comprising members spaced circumferentially of the pipe adapted to admit downflowing glass between the pipe and tube.

5. Apparatus as defined by claim 3 characterized by said spacing means comprising an annular member closing the upper end of the space between the tube and pipe.

6. In glass-forming apparatus, a blow-pipe journaled for rotation in an inclined position a sleeve surrounding the lower end of the pipe and adapted to serve as a shaping mandrel for a stream of molten glass flowing downwardly thereover, a plurality of nested, coaxial shells adjacent the lower end of the pipe and adapted to receive a tubular stream of glass from said sleeve, and means for supporting the shells for rotation with the pipe.

7. Apparatus as defined by claim 6 characterized by a bushing secured to the lower end of said pipe, and pins extending radially therefrom, said shells being mounted on said pins.

8. In glass-forming apparatus, an inclined mandrel mounted for rotation and adapted to receive a descending stream of glass on the exterior thereof, and glass-shaping means including a plurality of nested, coaxial shells mounted at the lower end of the mandrel coaxially therewith.

9. In glass-forming apparatus, an inclined mandrel mounted for rotation and adapted to receive a descending stream of glass on the exterior thereof, and glass-shaping means including a plurality of nested, coaxial shells mounted at the lower end of the mandrel coaxially therewith, the outermost of said shells being longer than other of said shells and extending axially upwardly beyond the upper ends of said other shells.

EDWARD DANNER.
